ATTORNEY

UNITED STATES PATENT OFFICE.

EUGENE WARD, OF NEWARK, NEW JERSEY.

SADDLE-CLIP FOR BICYCLES.

SPECIFICATION forming part of Letters Patent No. 551,016, dated December 10, 1895.

Application filed June 28, 1895. Serial No. 554,309. (No model.)

To all whom it may concern:

Be it known that I, EUGENE WARD, a citizen of the United States, residing at the city of Newark, Essex county, New Jersey, have 5 invented certain new and useful Improvements in Saddle-Clips for Bicycles and Similar Vehicles, of which the following is a specification.

My invention relates to a clip which is used 10 to secure the spring of the saddle to its supporting L-post; and it consists in the peculiar construction of the clip, as hereinafter more fully described.

In the drawings, Figure 1 is a side elevation 15 of my clip with a section of spring and of the L-post. Fig. 2 is a front view of the same. Fig. 3 is a bottom view of the key-wedge. Fig. 4 is a modification of the clip for holding a wire spring instead of a flat 20 spring. Fig. 5 shows a modification wherein a rod is substituted for the saddle-spring, and Fig. 6 is a top view of the key-wedge shown in Fig. 5.

Similar letters designate similar parts in 25 all the figures.

A is the body of the clip, which is formed or cast in a single piece, and is provided beneath its crown E with a suitable seat for the spring F, and is also provided with a seat C 30 for the L-post G. A key-wedge B is provided with arms e e and e' e' and is inserted in the clip A between the spring E and the L-post G, the recesses b and c in its ends allowing it to be adjusted from side to side of the clip.

35 The set-screw H passes through the clip A and bears with its end against the back of the key-wedge B, the forward end of which is supported by the inclined bearing D of the clip A, and by tightening the set-screw the 40 key-wedge will be driven tightly between the spring and the L-post, firmly locking them in place. By placing the set-screw at the side of the clip and between the L-post and spring I save the space that it would occupy if 45 placed below the L-post and am able to set the saddle lower upon the bicycle. The set-screw is also more conveniently accessible and the clip can be more readily adjusted as desired. In my clip, also, I provide carefully 50 fitted seats, of the whole thickness of the clip, for the spring and L-post, and clamp them

firmly in these seats by filling the intermediate space with the key-wedge B, which bears evenly with its entire width against their opposing faces, thus exerting its force within 55 the side lines of the clip and giving a direct and positive grip upon the spring and L-post over the whole length of their seats. This insures the holding of the spring and L-post with great steadiness in their seats and with 60 much less pressure and strain on the clip than is possible where the point of the set-screw is made to bear directly against one part, as the L-post, transmitting its force through that against the spring. It also avoids 65 the tendency to bend or warp the L-post or the spring, which tendency is exerted by clips wherein the seats do not afford continuous support in the direct line of the clamping pressure. Such clips have a constant tendency 70 to distort and strain the spring and L-post, requiring increased strength and weight of metal to resist such tendency; and in my construction the strain upon the clip is more evenly distributed and the pressure upon the 75 thread of the set-screw is greatly reduced.

The bearing D is inclined at an angle which, if extended, would coincide with the crown of the L-post G. The lower side of the key-wedge B, therefore, rests evenly upon the L- 80 post and the bearing D, and the key-wedge when pressed home is raised through its entire length uniformly against the lower side of the spring. Any tendency of the key-wedge to rock, and thereby grip one edge of 85 the spring more firmly than the other, is thus overcome, and the arms e e e' e', embracing the sides of the clip, prevent the lateral displacement of the key-wedge.

In Fig. 4 I have shown a modification of my 90 clip wherein the crown of the clip is provided with recessed seats i i to receive a wire spring I I instead of the flat spring F, and in Figs. 5 and 6 I have shown a further modification wherein the upper half of the clip is a duplication of the lower half, its seat C' corresponding with the lower seat C and being adapted to hold a saddle-rod G'. I have spoken of the saddle as being supported upon a spring; but it is obvious that the operation of the 95 clip will be the same whether it is used with a rigid support or with a spring. 100

Having thus described my invention, what I claim, and desire to secure by Letters Patent of the United States, is—

1. The combination, in a saddle clip, of a body or casting provided with a saddle-support seat and an L post seat, with a key-wedge adapted to be inserted between said seats, to lock the saddle-support and L post therein, substantially as described.
2. The combination, in a saddle clip, of a body or casting provided with a saddle-support seat, an L post seat, and an inclined key-wedge bearing, with a key-wedge adapted to be inserted between said seats, bearing with its forward end upon the inclined bearing of the clip body, to lock the saddle-support and L post in place, substantially as described.
3. The combination, in a saddle-clip, of a body or casting, provided with a saddle-support seat, an L post seat and an inclined key-wedge bearing, with a key-wedge, provided with arms to embrace the sides of the clip, and adapted to be inserted between the saddle-support and L post to lock them in their respective seats, substantially as described.
4. The combination, in a saddle-clip, of a body or casting, provided with a saddle-sup-

port seat, an L post seat and an inclined key-wedge bearing, a key-wedge, provided with arms to embrace the sides of the clip and 30 adapted to be inserted between the saddle-support and L post, to lock them in place, and a set screw to press said key-wedge into place, substantially as described.

5. The combination, in a saddle clip, of a body or casting, provided with a saddle-support seat in its upper portion, an L post seat in its lower portion, a set screw inserted through the side of said clip between said seats, a key-wedge, entering horizontally between the saddle-support and L post, to lock them in place, and being driven home by said set screw, substantially as described.

6. The combination in a saddle-clip of a body or casting provided with a saddle-support seat and an inclined key-wedge bearing, a key-wedge entering between said saddle-support seat and key-wedge bearing to lock the saddle-support in its said seat, and means for attaching said clip to the L-post.
